PAPERBOARD CARTON WITH SIFT-PROOF OPENING DEVICE AND RECLOSURE

Norman Kleiber, Upper Nyack, N. Y., assignor to Robert Gair Company, Inc., New York, N. Y., a corporation of Delaware

Application February 17, 1954, Serial No. 410,754

3 Claims. (CJ: 229-17)

The invention relates to a folding carton of paper-board and the like, and a blank therefor, having an improved sift-proof opening device and reclosure.

One of the most persistently recurring problems in the paper box business is that of designing folding cartons which can be glued up, filled and sealed with the use of conventional packaging machinery, and yet which will be adequately sift-proof. This problem has been especially difficult of solution where cartons are designed for easy opening, where special pouring openings are required, and where means are to be provided for reclosing the opening or pouring device. Generally speaking, the easier the carton can be opened or made ready for pouring of its contents, the less it is proof against sifting of its contents during shipment and handling. My invention is directed to the particular problem of providing an opening and reclosure device which is extremely easy to operate, yet which enables retention of adequate sift-proof construction and which is well adapted for handling in conventional packaging machinery.

Summary

My improved carton and carton blank comprises four side panels, an end flap adjoining each of the side panels, two opposed end flaps (usually the narrower ones) being foldable inwardly to form inner end flaps and the remaining two end flaps being foldable inwardly outside of the folded inner end flaps to form outer end flaps, a weakened line in the outer end flaps extending across the top of the carton parallel to the fold line of one of the inner end flaps, this weakened line being located where it is overlapped slightly by the end of the inner end flap just mentioned. A second weakened line extends at right angles to the first and divides in two that portion of the outer end flaps which overlies the inner end flap to which I have referred. This inner end flap is adhesively secured to the adjacent outer end flap structure over an area lying immediately adjacent the fold line. Other features of my invention will appear in the following

Description

In the drawings, wherein I have shown the best mode contemplated by me of carrying out my invention:

Fig. 1 is a perspective view of my carton in its preferred form and as a completed package.

Figs. 2 to 7 inclusive illustrate the steps of opening and reclosing the carton of Fig. 1, thus:

Fig. 2 shows the initial opening step of pressing inwardly to break open the carton.

Fig. 3 shows the second opening step.
Fig. 4 shows the third opening step.

Fig. 5 shows the first step in closing the carton.
Fig. 6 shows the second step in closing the carton.

Fig. 7 shows the reclosed carton.
Fig. 8 is a detail vertical sectional view of the carton.

Fig. 9 is a similar view, after the carton has been

opened and reclosed.

Fig. 10 is a face view of the blank from which the carton of Figs. 1 to 9 is formed.

Fig. 11 is a detail vertical sectional view of a modified form of opening and reclosing device, illustrating the first opening step, i. e. in this respect corresponding to Fig. 2...

Referring to Figs. 1 and 10, my improved carton and carton blank comprises four side panels **12**, **13**, **14**, **15**, an end flap adjoining each of the side panels (end flaps **16**, **17**, **18**, **19** respectively), two opposed end flaps **17**, **19** being foldable inwardly to form inner end flaps, the remaining two end flaps **16**, **18** being foldable inwardly outside of the folded inner end flaps to form outer end flaps, a weakened line **20**, **20'** in the outer end flaps extending across the top of the carton parallel to the fold line **28** of inner end flap **17**, the weakened line **20**, **20'** being located where it is overlapped slightly by the end of inner end flap **17**, and a second weakened line **21**, **21'** extending at right angles from the first weakened line **20**, **20'** and dividing in two that portion of the outer end flaps **16**, **18** which overlies inner end flap **17**. The several panels **12**, **13**, **14**, **15**, and end flaps **16**, **17**, **18**, **19**, are defined in the blank (Fig. 10) by the usual score lines **28** and cut lines **29**, the score lines determining the fold lines between the several panels and flaps. Glue lap extension **26** and panel **12** are folded over against panels **13** and **14**, and panel **15** is folded over panel **14** by bending on fold lines between panels **12** and **13** and **14** and **15** so that glue lap **26** becomes adhesively secured to the edge of the side panel **15** to produce the flat folded glued carton.

The weakened lines 20, 20', 21, 21' may be formed as perforations or as interrupted cut lines. In my preferred construction weakened lines 20, 21 in the outermost flap 18 are formed by perforations, and weakened lines 20', 21' in flap 16 are formed by interrupted cut lines. I have found that this particular arrangement combines strength in the outermost flap with ease of breaking open the carton at the weakened lines when ready for use.

40 use. Inner end flap 17 has a U-shaped cut line 22 forming tab 23 which can be pressed inwardly to provide a finger opening. The corners of flap 17 preferably are notched as shown at 30 for ease in performing the reclosing operation to be described.

45 An important feature of my opening device and re-closure is that inner end flap 17 is adhesively secured to the adjacent outer end flap structure over an area 27 lying immediately adjacent the fold line 28 of flap 17; i. e. the glued area extends from this fold line to the extent indicated at *a* in Figs. 3 and 10. This provides a good seal between the inner and outer end flaps while leaving flap 17 free over most of its area, making it very easy to break open the carton by pressing inwardly in the direction and general location indicated by the arrow

55 b in Fig. 2. It is particularly important to have a glued area lying immediately adjacent the fold line of the inner flap because, after the carton has been filled there usually is no support underneath the flaps during the sealing operation except near the edges and corners of the carton.
60 Therefore, if the glued area lies inwardly of the fold line, the inner end flap tends to curl away, resulting in poor adhesion. This difficulty is increased by reason of the fact that the wet adhesive tends to make the inner flap curl away from the first folded outer flap. One of the opening and reclosure devices heretofore proposed possesses the disadvantage that in order to make it operable the glued area between the inner and outer end flaps must be located some distance inwardly of the fold line.
65 This creates a serious problem in the packaging of finely powdered products such as soap powder, washing soda, cereals, etc., which can sift out through the corners during
70

shipment and handling. This is a problem of long standing which results not only in loss of contents of the packages but in defacing the outer printed or lithographed surfaces of the carton. During shipment when cartons are disposed one on top of another, the usual jouncing action caused by unevenness in roads or road beds in transportation by truck or rail, results in repeated inward pressures on the sides of the carton, producing what may be described as a bellows action which will blow out the fine contents of the cartons through the tiniest cracks; hence the great importance of preserving a strongly sealed area adjacent the fold line of the inner end flap. According to one mode of carrying out my invention, the outer surface of inner end flap 17 is treated with glue repellent ink except for the area 27 of the flap which lies immediately adjacent the fold line.

Referring now to Figs. 2 to 9 inclusive, I shall describe the operation of my improved opening device and reclosure. Fig. 8 shows the sealed carton before opening. The first step in opening the carton is to press inwardly in the direction and general location indicated by the arrow *b* in Fig. 2. This ruptures the weakened lines 20, 20', 21, 21', dividing in two that portion of the outer end flaps which overlies inner end flap 17 to produce flap sections 24 and 25. This is accomplished by pressing inwardly with the thumb or forefinger at the inner corner of section 24 or 25, or both. When the perforated and cut lines of the outer flaps have thus been broken through, the glued area 27 will break loose and the two sections 24, 25 can then be opened in shutter fashion as indicated in Fig. 3. Inner flap 17 is now free and can be opened as indicated in Fig. 4 by inserting the forefinger into the opening provided by pressing in tab 23, and pulling upwardly and outwardly. The carton is now ready for use.

To reclose the carton, the first step is to fold inwardly the flap sections 24 and 25 as indicated in Fig. 5. Then flap 17 is brought around as shown in Fig. 6, and its end tucked into the slot provided at the edges of sections 24 and 25. Figs. 7 and 9 show the reclosed carton in which the edge of flap 17 lies underneath the edge of the unopened portion of the carton top. Flap sections 24 and 25 press upwardly on flap 17 to maintain the latter in this tucked position.

In Fig. 11 I have illustrated a slightly modified construction in which the weakened line 20 of the outermost end flap 18 is slightly offset with respect to the corresponding weakened line 20' of the companion outer flap 16. Fig. 11 illustrates the first opening step in the modified construction, i. e. in this respect corresponding to Fig. 2. This offsetting of weakened lines 20 and 21 strengthens the construction and further helps to prevent sifting of the contents but does not interfere appreciably with the opening and reclosing operations.

A further advantage of my carton construction is that,

because weakened lines 20, 20', 21, 21' meet at a central point of the carton top, the corners of flap sections 24, 25 are free to be pressed inwardly, making it quite easy to open the carton. Also, since weakened line 21, 21' is well removed from the lateral edges of the carton top, there is very little tendency for the flaps 16 and 18 to break along such weakened line during the folding of these flaps in the packaging machine. This is helpful in avoiding "sifting" problems, because it insures a clean sharp fold at the fold lines of flaps 16 and 18, avoiding any tendency to pucker or to leave a channel through which powdered contents of the carton could sift.

The terms and expressions which I have employed are used in a descriptive and not a limiting sense, and I have no intention of excluding such equivalents of the invention described, or of portions thereof, as fall within the purview of the claims.

I claim:

1. A carton of paperboard and the like comprising four side panels, an end flap adjoining each of the side panels, two opposed end flaps being foldable inwardly to form inner end flaps and the remaining two end flaps being foldable inwardly outside of the folded inner end flaps to form overlapping outer end flaps, said inner and outer end flaps when folded comprising the top of the carton, a weakened line in the outer end flaps extending across the top of the carton parallel to the fold line of one of the inner end flaps, said weakened line being located where it is overlapped slightly by the end of said one inner end flap, and a second weakened line extending at right angles from the first named weakened line and spaced from the fold lines of said outer end flaps, said second weakened line dividing in two that portion of the overlapping outer end flaps which overlies said one inner end flap.

2. A carton as defined by claim 1 in which said one inner end flap is adhesively secured to the adjacent outer end flap structure over an area extending along the length of said fold line.

3. A carton as defined by claim 1 in which the first-named weakened line of the outermost of said overlapping outer flaps is slightly offset with respect to the corresponding weakened line of the companion outer flap.
